UNITED STATES PATENT OFFICE.

ALBERT RUSH, OF COLUMBUS, OHIO.

FLEXIBLE FIRE-RESISTING SHUTTER.

1,017,808.

Specification of Letters Patent. Patented Feb. 20, 1912.

Application filed March 4, 1908. Serial No. 419,150.

To all whom it may concern:

Be it known that I, ALBERT RUSH, a citizen of the United States, residing at Columbus, in the county of Franklin and State 5 of Ohio, have invented a certain new and useful Improvement in Flexible Fire-Resisting Shutters, of which the following is a specification.

The object of this invention is to provide 10 an improved flexible shutter or curtain that shall be of light construction, neat appearance, and that shall be adapted to resist fire or retard radiation of heat.

The invention is embodied in the construction hereinafter described and claimed, 15 the invention not being confined to the precise details of construction herein set forth and shown in the accompanying drawings for part hereof.

20 In said drawings—Figure 1 illustrates a sectional isometric perspective of fractions of the two slats and the device for hinging or connecting the slats together; Fig. 2 is a transverse vertical sectional view illustrating how the slats rock in the hinging member when the shutter or curtain is, for example, rolled up on a roller.

The slats proper are preferably formed or 30 molded out of plastic material, for example, of paper or wood pulp, or a mixture of materials that is fire-resistant or heat-retardant, or can be made so by coating or by admixture therewith of suitable materials. In 35 form the slats proper are shown in cross section and longitudinally to have a straight body portion 3 with hooks or rolls, as seen at 3^a and 3^b, on their opposite longitudinal edges, said rolls or hooks being formed on the arcs of circles internally and externally 40 to which the faces of the slat are respectively tangent. These hooks are shown to be located on or to project from the same side of the slat.

In some cases, to impart strength to the 45 slat and maintain its integrity when subjected to extreme heat, the slat can have embedded in it when molded a core of wire fabric as seen at 4. Said fabric can extend into the hooks. It is even practicable to

manufacture the slats of glass with the wire 50 screen embedded in them, such glass being known in the arts as "wire glass" and as constituting a good fire-resisting medium. When the slats are of wire glass a good fire- 55 resistant shutter or curtain for a window or door is afforded without excluding the light.

The device for connecting the slats, designated as a whole by the character 5, is 60 preferably made of a narrow strip of sheet-metal having its longitudinal halves bent to form two longitudinal pockets or seats 5^a and 5^b, one for each of a pair of the hooks 3^a and 3^b. The pockets 5^a and 5^b of the connecting device are shown to be adapted 65 to the form of hooks 3^a and 3^b, or so that said hooks rockingly fit in said pockets, the strip being depressed, as seen at 5^c, along its middle to secure conformity to the exterior sides of the hooks. 70

From an inspection of Fig. 2 it will be observed that the slats can be flexed or rocked with reference to each other in the connecting device for permitting the shutter or curtain to be rolled upon a roller or to pass 75 around a curved guiding channel. It will also be noted that the connecting device cooperates with the hooks to prevent undesirable movement of the slats edgewise together or asunder. In the construction 80 shown also the arc of the hook and pocket is such that the slat cannot be turned out of the pocket, hence the connecting device is applied by sliding it longitudinally on the hooks, or as may be desired, by sliding 85 the hook of a slat into the pocket of the connecting device.

The inner side of the curtain or shutter, that is, the side not containing the connecting devices, presents a smooth, chaste appearance. 90

What I claim and desire to secure by Letters Patent is:

A flexible shutter or curtain including in combination main slats of plastic material 95 having at their longitudinal edges rolls or hooks formed in cross section on the arcs of circles, said rolls or hooks in the slats

extending toward each other, and a connecting device for said main slats consisting of a metallic strip or slat bent at its opposite edges to form longitudinal pockets opening toward each other to receive the aforesaid rolls or hooks, said pockets having parallel inner walls concentric with the opposite sur-

faces of the aforesaid rolls or hooks and fitting against the said opposite surfaces of the hooks.

ALBERT RUSH.
